(57) **CLAIM**

The ornamental design for a throw-away tip for metal cutting tool, as shown and described.

DESCRIPTION

FIG. 1 is a front view of a first embodiment of a throw-away tip for metal cutting tool showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view thereof;

FIG. 8 is a sectional view taken along line 8-8 of FIG. 3 thereof;

FIG. 9 is a sectional view taken along line 9-9 of FIG. 3 thereof;

FIG. 10 is a front view of a second embodiment of a throw-away tip for metal cutting tool showing our new design;

FIG. 11 is a rear view thereof;

FIG. 12 is a top plan view thereof;

FIG. 13 is a bottom plan view thereof;

FIG. 14 is a left side view thereof;

FIG. 15 is a right side view thereof;

FIG. 16 is a perspective view thereof;

FIG. 17 is a sectional view taken along line 17-17 of FIG. 12 thereof; and,

FIG. 18 is a sectional view taken along line 18-18 of FIG. 12 thereof.

The broken lines shown in the drawings represent portions of the throw-away tip for metal cutting tool that form no part of the claimed design.
